CARBURETOR WITH IMPROVED CARBURATION

Adolf Heinrich, Munich, Germany

Application November 12, 1954, Serial No. 468,500

Claims priority, application Germany November 14, 1953

3 Claims. (Cl. 261—65)

There have already been known certain types of carburetor in which attempts were made to improve the manner in which carburation is carried out by providing for the ratio between the cross-sectional mixing area of the air duct and the diameter of the fuel discharge aperture to be varied in dependence on the speed of the engine and the load conditions.

In one known construction designed to attain this objective, use has been made of the well-known iris diaphragm for the purpose of determining the cross-sectional mixing area of the air duct and of varying said cross-sectional area. However, this attempted solution did not provide for the necessary dependability in operation, nor was it unaffected by trouble; for this reason, no carburetor of this type has ever been adopted in practice.

Another avenue that has been explored in an effort to render the hereinbefore mentioned ratio between cross sections variable, which avenue has also been tried, is to arrange for the venturi-like mixing nozzle surrounding the fixed fuel discharge nozzle to be slideable in the direction of the axis of the suction pipe. First it was tried by means of this arrangement to produce a sufficiently combustible mixture in the idling range of the engine by providing for the narrowest portion of the mixing nozzle to be sufficiently displaced in relation to velocities near the fuel discharge nozzle, whereafter the mixing nozzle was returned to its other extreme position where it remained as long as load conditions other than idling had to be met.

It has also been suggested to displace the slideable mixing nozzle not only between its two extreme positions in a single operation, but continuously and gradually to displace the mixing nozzle in relation to the fuel discharge nozzle, the said displacement in this case being a function of the position of the carburetor throttle valve.

All of these known suggestions according to which the mixing nozzle is displaced in relation to the fuel spray nozzle or according to which an iris diaphragm is used to vary the smallest cross section of the air duct have this in common: the change in the ratio between the cross section of the air mixing nozzle and that of the fuel spray nozzle is effected in one sense only, that is to say, with an increase in engine speed and/or an increase in the cylinder charge and/or an increase in the load imposed on the engine, the change in the size of the iris diaphragm opening or the movement of the mixing nozzle relative to the fuel discharge opening is always effected in one sense only. In all these cases the cross-sectional area of the air duct at the position of the fuel nozzle is enlarged as the output of the engine increases.

Now, in contrast to what has hitherto been known, the venturi-like mixing nozzle, which is arranged in a per se known manner to be displaced in the direction of the axis of the suction pipe, is arranged, according to the present invention, in such a manner that the position of the said nozzle is controlled in relation to the fixed fuel

2

spray nozzle of a carburetor in such a way that within the control range of the carburetor from idling conditions to full load conditions the mixing nozzle is reciprocated, whereby the narrowest portion of the mixing nozzle which is initially positioned at the approximate level of the fuel spray nozzle is first moved away from the aperture of the spray nozzle and is subsequently moved towards said aperture.

In this manner it is made possible to control the composition of the mixture in such way that a carburetor in which this arrangement is used is capable of improving the efficiency of power generation and of yielding favorable fuel consumption figures and operational transitions which have hitherto been impossible with known carburetor control methods.

The object of the invention is capable of meeting all known important requirements as regards the maintenance of a constant mixture composition and the preparation of a sufficiently combustible mixture for certain ranges of control.

The object of the invention takes care of the requirement of mixing small air flows with sufficient fuel in the idling range so as to produce a combustible mixture, and it also eliminates the well-known phenomenon of undesirable enrichment of the mixture at high engine speeds which is caused by the disparity between the resistance offered to the inflowing air and the flow resistance of the outflowing fuel, this disparity, in turn, being due to the fact that the first-named resistance increase at a greater rate than the last-named resistance.

The fact that the discharge opening of the spray nozzle is approximately positioned in the region of the narrowest cross section of the mixing nozzle when the engine is operating in the idling range, obviously meets the first of the two above-mentioned requirements in that high air flow velocities are set up at the spray nozzle aperture despite the small quantity of air drawn in per unit time; the positioning of the spray nozzle opening outside the narrowest cross section with the engine operating under part-load conditions permits fuel to be saved where it is possible without detracting from the efficiency with which power is developed; finally, the fact that within the full-load range the spray nozzle opening is again positioned within a smaller distance from the narrowest cross section of the mixing nozzle takes care of the requirement that within this load range fuel has to be introduced at a higher rate, while at the same time the undesirable enrichment of the mixture is counteracted by the vacuum acting on the spray nozzle aperture being reduced in relation to what it would be with the nozzle positioned at the narrowest portion of the mixing nozzle, this being due to the fact that in this control position the spray nozzle aperture is still slightly removed from the narrowest cross section of the mixing nozzle.

The details of the practical embodiment of the controls operating the said mixing nozzle are of no relevance as regards the principles underlying the present invention. The position of the mixing nozzle may be controlled in dependence on the position of the butterfly valve at any given moment and thus also in dependence on the factors thus controlled, which factors determine the power output of the engine, or the position of the mixing nozzle may be controlled, among other things, by the pressure existing in the air inlet of the engine, by the quantity of mixture admitted or by the speed of the engine, the control then being effected automatically, or by the provision of an adjusting linkage between the butterfly valve and the displaceable mixing nozzle, the said linkage establishing a positive interdependence between the movement of the two control organs.

It is impossible to state a generally applicable law governing this interdependence, that is, the dependence of

the length of travel of the mixing nozzle on the power data of the engine; it will be necessary to use empirical methods to establish the optimum pattern of the control actions for different types of engines and for different sets of operating conditions, this making it necessary for a carburetor the construction of which is based on the present invention to provide for easy adjustment of the controlled movements of the mixing nozzle as a function of those factors which affect the power output of the engine. Represented in the appended drawing is an illustrative embodiment of a carburetor according to the invention, there being provided between the butterfly valve of the carburetor and the displaceable mixing nozzle a linkage which is adapted to move these two control members in positively controlling interdependence, the said linkage being constructed in such a manner as to provide for easy adjustment of its individual links as regards their lengths and/or the position of their pivots so as to make it possible to vary the ratio between the controlling movements of the butterfly valve and the mixing nozzle for the purpose of adapting the control system to different types of engines and their various sets of operating conditions.

Figures 1, 2 and 3 of the appended drawing illustrate one and the same carburetor according to the invention, the said figures respectively showing the two extreme positions, i. e. those for idling and full-load conditions, and one intermediate position of the displaceable mixing nozzle. In the drawing, reference numerals indicate the various parts as follows: 1, the air intake opening; 2, the fuel discharge opening or fuel spray nozzle; 3, the venturi-like mixing nozzle which is adapted to be displaced in the direction of the axis of the suction pipe; 4, the butterfly valve or throttle; 5, the pivot axis of the throttle; 6, a lever mounted on the throttle pivot 5 and having a plurality of holes serving to attach at any of a variety of points the connecting rod 7 of the linkage provided between and linking together the mixture throttle 4 and the mixing nozzle 3; 8, an auxiliary pivot serving to operate the mixing nozzle 3; 9, a lever mounted on the said auxiliary pivot and having a plurality of holes serving to attach at any of a variety of points the other end of the connecting rod 7.

It will be appreciated that the embodiment illustrated as an example, having a control linkage 6, 7, 8, is adapted, by changing the effective length of the connecting rod 7 and by hooking its ends into suitably selected holes in the levers 6 and 9, respectively, to be adjusted within a wide

range to meet the requirements given by the type of engine under consideration and its various operating conditions.

The three different operative positions of the carburetor illustrated in the drawing indicate that with the butterfly valve fully opened the displaceable mixing nozzle has been almost completely returned to its original position which it assumes with the butterfly valve closed, and that with this particular position the aperture of the spray nozzle is still slightly removed from the narrowest portion or constriction of the mixing nozzle.

I claim:

1. A carburetor having a variably positioned pivotal butterfly valve, air intake means, fuel spray means between said butterfly valve and said air intake means, a mixing nozzle movably positioned adjacent said fuel spray means, and control means responsive to variations in position of said butterfly valve for moving said mixing nozzle away from and thereafter back toward said fuel spray means as the position of said butterfly valve is increasingly varied in a single preselected direction, said control means comprising a first pivotal arm coupled to said butterfly valve and movable therewith, a second pivotal arm connected to said mixing nozzle, and a linking arm connected to both said first and second pivotal arms whereby unidirectional variations in position of said butterfly valve effect bidirectional variations in the position of said mixing nozzle.

2. The carburetor of claim 1 including means for variably connecting said linking arm at differing positions on each of said first and second pivotal arms.

3. The combination of claim 1 wherein said mixing nozzle comprises venturi means having a region of restricted cross-section, said control means being operative to position said restricted region substantially adjacent said fuel spray means for both closed and fully opened positions of said butterfly valve.
